his attorney.

UNITED STATES PATENT OFFICE.

CHARLES GOUDET, OF GENEVA, SWITZERLAND, ASSIGNOR TO THE FIRM OF SOCIÉTÉ D'ÉTUDES CHIMIQUES POUR L'INDUSTRIE, OF GENEVA, SWITZERLAND.

PROCESS AND APPARATUS FOR FRACTIONAL DISTILLATION OF LIQUIDS.

1,312,974.

Specification of Letters Patent.

Patented Aug. 12, 1919.

Application filed February 27, 1919. Serial No. 279,570.

To all whom it may concern:

Be it known that I, CHARLES GOUDET, a citizen of Switzerland, residing at Geneva, Canton of Geneva, in the Confederation of Switzerland, have invented certain new and useful Improvements in Improved Processes of and Apparatus for Fractional Distillation of Liquids, of which the following is a specification.

10 The present invention relates to a process of and apparatus for the separation of volatile liquids by fractional distillation by the employment of a dephlegmator maintained at a predetermined temperature by the ebullition of a liquid under pressure. The temperature of this ebullition of the liquid under pressure may be regulated and modified as desired by raising the pressure above the atmospheric pressure.

20 The drawing is a central longitudinal cross section of an apparatus for carrying out my invention.

25 *a* is a boiler which is provided with a dome in which there is a return condenser *b* and a safety valve *c*. In this boiler a dephlegmator or condensing and separating chamber *d* is arranged. *e* represents contact bodies filling the dephlegmator *d*. These contact bodies may be closely wound coils 30 of small cylinders of wire gauze or any other well known contact bodies. The dephlegmator is connected at one end by a tube *f* to a distilling apparatus not shown in the drawing, and at the other end by the tube *g* to a condenser also not shown in the drawing. *h* is a coiled pipe for the passage of steam intended to heat the contents of the boiler but which as will be understood may be heated by a fire or any other source of 40 heat.

45 When the constituents of a mixture of several liquids such as for instance the three isomers of xylene, boiling at different temperatures are to be separated, the temperature within the boiler *a* is first maintained at about 136° centigrade by heating water or any other liquid under pressure in order to separate the paraxylene which boils approximately at this temperature and the vapors of which are then carried away by the pipe *g* to the condenser to which reference has hereinbefore been made. After all the paraxylene has thus been separated the pressure in the boiler is raised by regulating the 50 valve *c* in order to raise the temperature

sufficiently to separate the metaxylene which boils at 139.2° C., and the metaxylene is then passed from the dephlegmator to the pipe *g* and thence to the condenser to which reference has hereinbefore been made.

60 This apparatus offers a natural advantage over the hitherto known apparatus in which the condensing liquid is maintained boiling and at a constant temperature by reducing the pressure within the boiler containing this liquid, because it is easier in practice to raise than to reduce the pressure.

65 The condensing liquid may vary according to the degree of temperature to be obtained in the boiler *a*. It may consist of 70 water, benzene or other more or less volatile liquids. The vapors which are produced in the boiler are constantly condensed by the condenser *b* and the condensed liquid flows back into the boiler. The dephlegmator *d* 75 may be connected to the distillation tower by means of an intermediate pipe in order to bring back to this tower the liquid which in some cases is condensed and remains in the dephlegmator. Any form of dephlegmator may be employed.

80 I claim as my invention:

85 1. The hereinbefore described process of separating volatile liquids by fractional distillation consisting in passing the volatiles to be separated to a dephlegmator, maintaining the dephlegmator at a given temperature for a predetermined period and then varying the temperature of the dephlegmator by varying the pressure of the medium 90 by which the dephlegmator is heated.

95 2. The hereinbefore described process of separating volatile liquids by fractional distillation consisting in passing the volatiles to be separated to a dephlegmator, maintaining the dephlegmator at a given temperature for a predetermined period, and then raising the temperature of the dephlegmator by increasing the pressure of the medium 100 by which the dephlegmator is heated.

105 3. The hereinbefore described process of separating volatile liquids by fractional distillation consisting in passing the volatiles to be separated to a dephlegmator, and successively increasing the temperature of the dephlegmator at predetermined intervals by correspondingly increasing the pressure on the medium in which the dephlegmator is heated.

110 4. An apparatus for separating volatile

liquids by fractional distillation comprising a vessel, a dephlegmator in said vessel, means for heating and condensing a dephlegmator heating medium contained within said vessel, and means for regulating the pressure of the said heating medium.

5. An apparatus for separating volatile liquids by fractional distillation comprising a boiler adapted to contain a heating medium, a dephlegmator in the heating medium within the said boiler, connections leading to and from the said dephlegmator through the walls of the said boiler, and means for varying the pressure on the heating medium in the boiler.

10. An apparatus for separating volatile

liquids by fractional distillation comprising a boiler adapted to contain a heating medium, a dephlegmator in the heating medium within the said boiler, connections 20 leading to and from the said dephlegmator through the walls of the said boiler, a condenser located in a dome forming part of the said boiler, and a pressure valve in the upper portion of the said dome.

15. In testimony whereof I have affixed my signature in presence of two witnesses.

CHARLES GOUDET.
